UNITED STATES PATENT OFFICE

JOHN MENTGES, OF SIDNEY, OHIO, ASSIGNOR, BY MESNE ASSIGNMENTS, TO DEXTER
FOLDER COMPANY, OF NEW YORK, N. Y., A CORPORATION OF NEW YORK

PAPER-FOLDING MACHINE

Application filed November 8, 1926. Serial No. 146,936.

The present invention is an improvement in folding mechanisms.

Certain objects of the invention are to provide a compact construction comprising a novel combination and arrangement of loop folders and a knife folder, for making a plurality of folds, either in news or book imposition, and to provide such a construction in which no parts are removed or added in changing the number or arrangement of folds to be made.

A further object of the invention is to provide a single packer adapted to receive the folded sheets that have been operated on by the knife folder alone, or by the knife folder and one or more of the loop folders.

These objects, among others, are secured by said novel arrangement of loop and knife folding mechanisms, in combination with deflecting mechanisms which selectively direct the sheets to the desired folding mechanism or mechanisms.

With respect to the utilization of a single packer for receiving the sheets which have been operated on by the knife folder alone, or the knife folder and a succeeding folding mechanism, the object is preferably attained by positioning of loop folding mechanisms for imparting news or book imposition beneath the knife folder, preferably with the packer symmetrically positioned with respect to said loop folding mechanisms.

I shall now describe the structure and operation of my invention, with the assistance of the accompanying drawings. In these drawings,

Fig. 1 is a plan view of my machine, with the feed table and a few other parts removed, to expose important parts situated below the table;

Fig. 2 is a side elevation of the machine, showing the feed table and parts omitted in Fig. 1;

Fig. 3 is an end elevation of the machine looking from the right of Figs. 1 and 2. In this figure one of the packing devices is omitted;

Figs. 4, 5 and 6 are views of the deflector which may be employed;

Figs. 7 and 8 show twelve pages folded

news imposition and book imposition, respectively.

Referring now to Figures 1, 2 and 3, the machine preferably contains five folding mechanisms, indicated generally by letters A, B, C, D and E, though for some purposes a greater or less number may be employed. Mechanism A is a loop folder having plates or grids 25 and 26, secured together with a space 27 between them. As is customary in the art these assembled grids, 25 and 26, are also referred to collectively as a "grid." This grid carries rods 28 on which a stop 29 is adjustably secured. At the mouth of the grid, three rollers 30, 31 and 32 are mounted, and connected by suitable pinions (not shown) to rotate them in unison in directions indicated by arrows. Mechanisms B, D and E are preferably similar to mechanism A, except that the grid plates 25 and 26 lie in a horizontal instead of an oblique plane.

Mechanism C is a knife folder and comprises folding rollers 40 and 41, connected by gears (not shown) to rotate in the directions indicated by arrows in Fig. 3. A plurality of belts or tapes 42 carry sheets from mechanism A to a stop 43. These belts run on pulleys 44 and are driven by suitable means not shown. A knife 45 is mounted on a rocker arm 46, and at suitable intervals the arm is rocked downward by means not shown, to tuck sheets lying on the tapes between the rolls 40 and 41.

Just below the bite of rolls 31 and 32 (see Fig. 2) a deflector, indicated generally by the numeral 50, is mounted on trunnions 51 and 52. See also Figs. 4, 5 and 6. This deflector may, if desired, be of the type illustrated and claimed in my application Serial No. 30,149, filed May 14, 1925, which consists of two plates or strips, 53 and 54, with a space 55 between them. Rigidly mounted on the trunnion 52 is an arm 56, which carries a stud 57 at its free end. This arm may be rocked to any of three positions, and then by an endwise movement of the whole deflector structure the stud 57 is inserted in one of three holes 58 in the frame of the machine, thereby holding the deflector in the desired

position. The stud is yieldingly held in the hole 58 by a compression spring 59, surrounding the trunnion 52 and confined between the end of the deflector and the frame of the machine. A similar deflector, preferably made and controlled in the same manner, is mounted below the bite of rolls 40 and 41 of the knife folder C. See Fig. 3. The deflectors are operated by knurled knobs secured to the end of the trunnion 52.

A feed table 60 is situated above the knife folder C, and is arranged to be swung upward (see dotted line Fig. 2) to provide easy access to the folding mechanism C. Sheets are fed to mechanism A from this table periodically by any suitable means 61, shown in Fig. 2, this device being operated in timed relation with the knife of the folding mechanism C, by means not shown.

It is not necessary to describe the operation of the folding mechanism A as this is well understood. It suffices to say that sheets enter at the bite of rolls 30-31 and emerge folded from between rolls 31-32. In Fig. 2 the deflector 50 is shown in full lines in such position that as sheets emerge from the rolls 31-32 they are deflected to the right onto the belts 42, whereby they are carried to the stop 43, which in Fig. 2 is indicated by dotted lines. The knife 45 then descends and tucks the sheet into the bite of rolls 40-41, thus imparting a fold to them at a right angle to the fold made by mechanism A. Referring now to Fig. 3 it will be seen that the deflector 50 occupies one oblique position, and as the sheets emerge from the rolls 40-41 they are deflected to the right into the mechanism E, where they receive a fold parallel to the fold received in mechanism C. If the deflector is moved to its other oblique position indicated in dotted lines in Fig. 3, the sheets will be deflected to the mechanism D instead of to E. In either case, the sheets are delivered to the packer. If the deflector is moved to its central vertical position indicated in dotted lines in Fig. 3, the sheets pass between plates 53, 54 and drop directly from mechanism C to the packer.

The packer preferably comprises a base 70 on which two vertical walls 71-71 are adjustably mounted. Each wall carries two cleats 72-72, between which the ends of the folded sheets are confined until the sheets are pushed past the left hand cleat by the reciprocating pusher 73. Deflectors 74-74 carried by the walls 71 serve to deflect the sheets into the space between cleats 72-72, as they emerge from the folding mechanism, and while they are still under the control of folding mechanism D or E. This packer is preferably of the type illustrated and claimed in my application Serial No. 146,935 filed November 8, 1926. If the deflector 50 be turned to its intermediate or vertical position, sheets drop through the deflector, that is, between

the plates 53 and 54, and between the stationary deflector plates 74-74, into the packer, mechanisms D and E remaining idle. A similar packer is employed to receive folded sheets from mechanisms A and B, as herein-after described.

Whether the fold is to be made in mechanism D or E, is determined by whether news or book imposition is desired. Fig. 7 shows an example of news imposition, and it will be seen that the sheet is folded with the head outside. Fig. 8 shows an example of book imposition, the head being folded inside, both forms being largely used in practice, and each filling a particular want.

Referring more particularly to Fig. 2, it will be seen that the deflector 50 below the folding mechanism A may be rocked from its full line angular position to the dotted line angular position, and sheets will then be deflected to mechanism B instead of to mechanism C. In that case a sheet will receive a fold parallel to that imparted in mechanism A, instead of this fold being at a right angle to the preceding fold, and the folded sheet will be delivered from mechanism B to the packer adjacent thereto. When the deflector is in its central or vertical dotted line position sheets pass between the plates 53 and 54 and drop directly from mechanism A to the packer.

By reference to the accompanying drawings it will be observed that the feed table is arranged above the knife folder C and folders D and E, and that folders D and E are arranged symmetrically beneath the knife folder, the packer being symmetrically arranged with respect to folders D and E. This arrangement makes it possible to place the whole machine, comprising in this case five folding mechanisms, within the space required for folding mechanisms A and B and the feed table.

By positioning mechanism C adjacent to mechanism B and providing a deflector for directing papers to one or the other at will, I am enabled to make a second fold either parallel or at a right angle to the fold imparted by mechanism A. By this construction I am also able to deliver folded sheets to one of two packers, whether these sheets emerge from mechanism A, B, C, D or E.

Similar advantages of simplicity and compactness may be attained by this type of construction, whether mechanism D and E are both loopers, both knife folders, or one looper and one knife folder.

It is to be understood that the combination of the knife folding mechanism, the deflector and the loop folding mechanisms for securing either book or news imposition may be preceded or followed by other folding mechanisms, whether knife or loop.

What is claimed is:

1. In a folding machine, the combination of

a loop folding mechanism, a knife folder receiving the sheets therefrom, two loop folding mechanisms adapted selectively to receive the sheets from said knife folder, and a deflector 5 for directing the sheets to one or the other of said last mentioned loop folding mechanisms.

2. In a folding machine, the combination of a loop folding mechanism, a knife folder receiving the sheets therefrom, a plurality of 10 loop folding mechanisms, and a deflector adapted selectively to direct the sheets into said mechanisms to produce news or book imposition.

3. In a folding machine, the combination 15 of a loop folding mechanism, a knife folder receiving the sheets therefrom, two folding mechanisms adapted selectively to receive the sheets from said knife folder, and a deflector for directing the sheets to one or the other of 20 said last mentioned folding mechanisms.

4. In a folding machine, the combination of a loop folding mechanism, a knife folder receiving the sheets therefrom, two loop folding mechanisms, adapted selectively to 25 receive the sheets from said knife folder, a packer adapted to receive the sheets from the knife folder or either one of the last mentioned loop folding mechanisms, and a deflector adapted selectively to deliver the 30 sheets from the knife folder to either one of the last mentioned loop folding mechanisms, or allow the sheets to drop directly to the packer.

5. In a folding machine, the combination of 35 a loop folding mechanism, a knife folder receiving sheets therefrom, a plurality of loop folding mechanisms, a packer adapted to receive sheets from the knife folder or the last mentioned loop folding mechanisms, and a deflector adapted selectively to deliver the 40 sheets from the knife folder to the loop folding mechanisms for imparting book or news imposition.

6. In a folding machine, the combination 45 of a feed table, a knife folder arranged beneath the same, means for delivering sheets from the feed table to the knife folder, a plurality of folding mechanisms arranged beneath the knife folder, and a deflector adjustably positioned to deliver sheets from said 50 knife folder to one or the other of said mechanisms, or allow the sheets to drop between said mechanisms.

7. In a folding machine, the combination of 55 a feed table, a knife folder arranged beneath the same, means for delivering sheets from the feed table to the knife folder, said feed table being hinged at one end to allow access to said knife folder, a plurality of folding 60 mechanisms arranged beneath the knife folder, and a deflector adjustably positioned to deliver sheets from said knife folder to one or the other of said mechanisms, or allow the sheets to drop between said mechanisms.

8. In a folding machine, the combination

of a feed table, a knife folder arranged beneath the same, means for delivering sheets from the feed table to the knife folder, a plurality of folding mechanisms arranged beneath the knife folder, a deflector adjustably positioned to deliver sheets from said knife folder to one or the other of said mechanisms, or in a third path between said mechanisms, and a packer arranged to receive the sheets from both of said mechanisms and also the sheets traversing the third path between 75 said mechanisms.

9. In a folding machine, the combination of a feed table, a knife folder arranged beneath the same, means for delivering sheets from the feed table to the knife folder, a plurality of folding mechanisms arranged beneath the knife folder, a deflector adjustably positioned to deliver sheets from said knife folder to one or the other of said mechanisms, or in a third path between said mechanisms, and a packer arranged to receive the sheets from both of said mechanisms and also the sheets traversing the third path between 80 said mechanisms, said mechanisms being symmetrically arranged with respect to said knife folder, and said packer being symmetrically positioned with respect to said mechanisms.

10. In a folding machine, the combination of a feed table, a knife folder arranged beneath the table, means, including a folding device, for delivering sheets from said table to said knife folder, a plurality of folding mechanisms arranged beneath the knife folder, and a deflector adjustably positioned 95 to deliver the sheets from said knife folder to one or the other of said mechanisms, or in a third path between said mechanisms.

11. In a folding machine, the combination of a feed table, a knife folder arranged beneath the same, means, including a folding device, for delivering sheets from said table to said knife folder, a plurality of folding mechanisms arranged beneath the knife folder, a deflector adjustably positioned to 100 deliver the sheets from said knife folder to one or the other of said mechanisms, or in a third path between said mechanisms, and a packer arranged to receive the sheets from both of said mechanisms, and also the sheets traversing the third path between said mechanisms.

12. In a folding machine, the combination of a feed table, a knife folder arranged beneath the same, said feed table being hinged at its forward end to allow access to said knife folder, means, including a folding device, for delivering sheets from said table to said knife folder, a plurality of folding mechanisms arranged beneath the knife folder, a deflector adjustably positioned to deliver the sheets from said knife folder to one or the other of said mechanisms, or in a third path between said mechanisms, and a packer arranged to receive the sheets from 110 115 120 125 130

both of said mechanisms, and also the sheets traversing the third path between said mechanisms.

13. In a folding machine, the combination of a feed table, a knife folder arranged beneath the same, means, including a folding device, for delivering sheets from said table to said knife folder, a plurality of folding mechanisms arranged beneath the knife folder, a deflector adjustably positioned to deliver the sheets from said knife folder to one or the other of said mechanisms, or in a third path between said mechanisms, and a packer arranged to receive the sheets from both of said mechanisms, and also the sheets traversing the third path between said mechanisms, said mechanisms being symmetrically arranged with respect to said knife folder, and said packer being symmetrically positioned with respect to said mechanisms.

14. In a folding machine, the combination of a loop folding mechanism, two succeeding folding mechanisms, one of which is a loop folding mechanism adapted to produce a fold parallel to said first loop mechanism, the other a knife folder producing a fold at a right angle to that imparted by the first fold mechanism, and a deflector adapted selectively to direct sheets from the first mentioned mechanism to either of the succeeding mechanisms, and also in a third direction between said mechanisms.

15. In a folding machine, the combination of a folding mechanism, two succeeding folding mechanisms, one of which produces a fold parallel to the first, the other a fold at a right angle to the first, and a deflector adapted selectively to direct sheets from the first mentioned mechanism to either of the succeeding mechanisms, or in a third direction between said mechanisms.

16. In a folding machine, the combination of a loop folding mechanism, two succeeding folding mechanisms, one of which is a loop folding mechanism adapted to produce a fold parallel to said first loop mechanism, the other a knife folder producing a fold at a right angle to that imparted by the first fold mechanism, a deflector adapted selectively to direct the sheets from the first mentioned mechanism to either of the succeeding mechanisms, or in a third direction between said mechanisms, and a packer positioned to receive sheets delivered direct from the first mentioned mechanism, and also from the succeeding parallel mechanism.

17. In a folding machine, the combination of a folding mechanism, two succeeding folding mechanisms, one of which produces a fold parallel to the first, the other a fold at a right angle to the first, a deflector adapted selectively to direct sheets from the first mentioned mechanism to either of the succeeding mechanisms, or in a third direction between said mechanisms, and a packer positioned to re-

ceive sheets delivered direct from the first mentioned mechanism, and also from the succeeding parallel mechanism.

18. In a folding machine, the combination of a loop folding mechanism, a folding mechanism to which sheets pass therefrom by a movement wholly normal to the rolls of the loop mechanism, and whereby they are folded at a right angle to the fold imparted by said loop mechanism, two succeeding folding mechanisms, each adapted to impart a fold parallel to said right angle fold, and a deflector whereby to direct the sheets to one or the other of said parallel fold mechanisms.
